UNITED STATES PATENT OFFICE

173,074

COMBINED OTTOMAN AND RECEPTACLE

Kenneth C. McMaster, Toledo, Ohio

Application November 20, 1952, Serial No. 22,377

Term of patent 14 years

(Cl. D15—1)

To all whom it may concern:

Be it known that I, Kenneth C. McMaster, a citizen of the United States, residing at Toledo, county of Lucas, State of Ohio, have invented a new, original, and ornamental Design for a Combined Ottoman and Receptacle, of which the following is a specification, reference being had to the accompanying drawing, forming a part hereof.

Fig. 1 is a perspective view of a combined ottoman and receptacle, showing my new design; and

Fig. 2 is a perspective view of said combined ottoman and receptacle with the lid and drawers in open position.

The sides of the ottoman body not shown are the same as the sides shown in Fig. 1.

I claim:

The ornamental design for a combined ottoman and receptacle, substantially as shown and described.
